(57) **CLAIM**

The ornamental design for an ergonomic hand grip, as shown and described.

DESCRIPTION

FIG. 1 is a perspective view of the ergonomic hand grip of the present invention;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a perspective view of an alternate embodiment of the ergonomic hand grip of the present invention;

FIG. 9 is a right side view thereof;

FIG. 10 is a left side view thereof;

FIG. 11 is a front view thereof;

FIG. 12 is a back view thereof;

FIG. 13 is a top view thereof; and,

FIG. 14 is a bottom view thereof.

The broken lines in the drawings are included to show features on the ergonomic hand grip that form no part of the claimed design.

1 Claim, 7 Drawing Sheets---
